UNITED STATES PATENT OFFICE.

THEODORE McMASTER, OF NEW YORK, N. Y.

WRENCH.

No. 806,701.

Specification of Letters Patent.

Patented Dec. 5, 1905.

Application filed March 16, 1905. Serial No. 250,329.

To all whom it may concern:

Be it known that I, THEODORE McMASTER, a citizen of the United States, and a resident of the borough of Brooklyn, of the city of 5 New York, State of New York, have invented certain new and useful Improvements in Wrenches, of which the following is a specification, reference being had to the accompanying drawings, forming a part hereof.

10 The object of this invention is to provide a wrench in which the jaws can be quickly and easily adjusted to the desired position, where they will remain without any variation. In the common monkey-wrench one of the jaws 15 is generally provided with a threaded shank portion through which this jaw is screwed toward or from the other jaw, thus bringing the jaws into the desired relative positions. It is desirable to eliminate, if possible, the 20 screw adjustment in wrenches of this sort, inasmuch as this method of adjustment is slow and as the jaws in such wrenches when set do not remain absolutely in their fixed position.

25 In the drawings where a monkey-wrench embodying the invention is illustrated, Figure 1 is a view in side elevation of the wrench, and Fig. 2 is a view in elevation looking from the right in Fig. 1.

30 The stationary jaw may have, as usual, a shank portion *a*, upon which a handle *b* may be secured, while the head *c* of the stationary jaw is preferably cut away to permit the shank *d* of the movable jaw to extend therethrough. The lower end of the shank of the movable jaw preferably embraces, by means 35 of a slotted extension *e*, the shank of the stationary jaw, which is formed with a stop at *f* to prevent the travel of the extension *e* beyond this point. The head *g* of the movable jaw 40 caps the wrench and being extensible beyond the head *c*, which is always between the head *g* and its shank *a*, obviously gives the wrench a greater leverage for large nuts—that is, 45 when the jaws are widely separated—than for small nuts, which only require a short extension of the movable jaw.

In order to provide for a quick adjustment of the jaws to the desired opening and to insure an invariability of position when the 50 jaws have been set, one of the jaws, preferably the movable jaw, is provided with a ratchet *h*, which coöperates with the corre-

sponding ratchet *i* on a lever *k*, pivoted to the other jaw—that is, the stationary jaw— 55 at *l*. The ratchet-teeth on the lever and on the movable jaw are such as to absolutely prevent the movable jaw from being extended while the ratchets engage each other, but to freely permit the movable jaw to be 60 moved in a direction to close the jaws. The lower end of the lever *k* preferably embraces the shank of the stationary jaw below the extension-piece *e* and presents a presser-piece *m* near the handle for the thumb. By this 65 means the lever *k* may be pressed backward against the action of a spring *n*, which normally holds it yieldingly in its forward position, and thus brings the ratchet on the lever into engagement with the ratchet on the 70 movable jaw.

When the wrench is in use, the movable jaw is readily extended by the pressure of the thumb upon the presser-piece *m*, the wrench being held with its head downward and the 75 jaw dropping by gravity as soon as it is released by the disengagement of the ratchets. When the movable jaw has been extended, the pressure of the thumb on the presser-piece *m* is released and the ratchets again 80 engage with each other. The movable jaw may, notwithstanding the engagement of the ratchets, be moved backward upon the stationary jaw, thereby bringing the two jaws together upon a nut or other object upon 85 which it is desired that the jaws shall close, or the movable jaw may be moved back until the opening between the jaws is of the desired extent. It will be obvious that when the jaws close upon a nut or other object the 90 position of the movable jaw remains fixed, and said jaw is absolutely inextensible so long as the ratchets engage each other.

I claim as my invention—

1. In a wrench, the combination of a stationary jaw having a head and a shank, a movable jaw extending through the head and embracing the shank of the stationary jaw, a ratchet on the movable jaw, and a lever secured to the stationary jaw and having 95 a ratchet, said lever resting normally with the teeth of its ratchet engaging the teeth of the ratchet on the jaw.

2. In a wrench, the combination of a stationary jaw having a head and a shank, a 100 movable jaw having a head and a shank, the

shank of the movable jaw embracing the shank of the stationary jaw and extending through the head of the stationary jaw, and the head of the stationary jaw resting between its shank and the head of the movable jaw, a ratchet on the shank of the movable jaw, a lever pivoted to the head of the stationary jaw and having a ratchet, and a

spring to hold the ratchet on the lever against the ratchet on the movable jaw. 10

This specification signed and witnessed this 11th day of March, A. D. 1905.

THEODORE McMASTER.
